ABSTRACT

A wall support system may include a top support plate locatable on a top surface of a floor of the above ground level; a bottom support plate locatable beneath the top support plate on a bottom surface of the floor; a securing means for securing the top support plate to the bottom support plate; a bottom support prop having a first end configured to be coupled to the bottom support plate and a second end configured to be coupled to a load bearing structure associated with the multi-level building; and a top support prop having a first end configured to be coupled to the top support plate and a second end configured to be attached to an inner surface of a pre-cast concrete slab wall substantially vertically positioned on the floor of the above ground level.

**WALL SUPPORT SYSTEM AND METHOD
FOR CONSTRUCTING MULTISTORY
BUILDINGS**

**CROSS-REFERENCE TO RELATED
APPLICATIONS**

This application claims priority to, and hereby incorporates by reference in its entirety for all purposes, Australia Patent Application No. 2023202437, filed Apr. 20, 2023 and entitled "A WALL SUPPORT SYSTEM AND METHOD FOR CONSTRUCTING MULTISTORY BUILDINGS."

TECHNICAL FIELD

The present invention relates to a wall support system which is particularly configured for the rapid construction of a multi-level building and more particularly to a multi-level building having walls formed from pre-cast concrete.

BACKGROUND

Any discussion of documents, acts, materials, devices, articles or the like which has been included in this specification is solely for the purpose of providing a context for the present invention. It is not to be taken as an admission that any or all of these matters form part of the prior art base or were common general knowledge in the field relevant to the present invention as it existed in Australia or elsewhere before the priority date of this application.

Concrete panels are becoming increasingly common for use in constructing multi-story buildings and can be used for forming floors, walls and ceilings. Conventionally, concrete panels were formed on site. However, in-situ panel formation is time consuming due to the time required to form the slab and wait for the concrete to sufficiently cure. As such, the industry has moved toward using pre-cast concrete panels that are formed off-site (and often in advance of the build) and shipped when ready to be installed. Pre-cast panels are thus well suited for rapid construction, significantly reducing the time from project approval to occupancy.

A method of constructing buildings using pre-cast concrete panels is described in the Applicant's Australian Patent No. 2021107586 ("the '586 Patent"), entitled "Construction of a building using precast panels," which was granted on Dec. 15, 2021, published on Jan. 6, 2022, the entire contents of which are hereby incorporated herein by reference for all purposes. The disclosure details a construction method whereby novel brackets and joining techniques are used to assemble and join precast concrete wall panels. At ground level, wall panels are anchored to and supported by a concrete floor slab.

The method disclosed in the '586 Patent extends to use in forming upper levels of a multi-level building, where the ground level precast wall panels are used to support a timber floor truss system of the upper level. However, due to the substantial weight of the precast wall panels and a lack of any structural footing foundation to which the panels can be anchored on the upper level, it can be particularly difficult to support said upper-level wall panels during construction.

It would be advantageous if there was provided a technique for supporting precast concrete walls panels during construction of an upper level of a multi-level building.

SUMMARY

This summary represents non-limiting embodiments of the disclosure.

2

In some aspects, the techniques described herein relate to a wall support system for use in constructing walls of an above ground level of a multi-level building, the wall support system including: a top support plate locatable on a top surface of a floor of the above ground level; a bottom support plate locatable beneath the top support plate on a bottom surface of the floor of the above ground level; a securing means for securing the top support plate to the bottom support plate, thereby sandwiching a portion of the floor of the above ground level therebetween; a bottom support prop having a first end configured to be coupled to the bottom support plate and a second end configured to be coupled to a load bearing structure associated with the multi-level building; and a top support prop having a first end configured to be coupled to the top support plate and a second end configured to be attached to an inner surface of a pre-cast concrete slab wall substantially vertically positioned on the floor of the above ground level, wherein the top support prop is configured to extend diagonally from the top support plate to the pre-cast concrete slab wall to support the pre-cast concrete slab wall during construction of the multi-level building.

In some aspects, a length of the top support prop is adjustable to set a vertical positioning of the pre-cast concrete slab wall.

In some aspects, the bottom support plate is configured to bear against a joist, beam, or other floor support structure.

In some aspects, the securing means includes one or more bolts each having a threaded end that passes through a respective opening in the top support plate, extends through a hole in the floor of the above ground level and out a corresponding opening in the bottom support plate for receiving a nut.

In some aspects, the top support plate further includes a top plate projection which extends upwardly from an outer surface terminating in a flanged end and wherein the first end of the top support prop includes a connecting plate having an opening defined therein for receiving the top plate projection.

In some aspects, the top plate projection includes a bolt having a threaded end that is received within a threaded opening defined in the top support plate and wherein the bolt is screwed into the threaded opening for securing the top support prop to the top support plate.

In some aspects, the connecting plate is pivotable with respect to a longitudinal body of the top support prop and wherein, in use, the connecting plate lies flat on the outer surface of the top support plate.

In some aspects, the second end of the top support prop includes a connecting plate which is pivotable with respect to the longitudinal body of the top support prop and which includes an opening defined therein for receiving the securing means for securing the top support prop to the inner surface of the pre-cast concrete slab wall.

In some aspects, the top support plate further includes a second projection which extends upwardly from the outer surface of the top support plate and wherein the first end of a second top support prop includes a connecting plate having an opening defined therein for receiving the second projection and such that in use a second end of the second top support prop connects to a second pre-cast concrete wall.

In some aspects, the bottom support plate further includes a bottom plate projection which extends away from an outer surface terminating in a flanged end and wherein the first end of the bottom support prop includes a floor prop connecting plate having an opening defined therein for receiving a body of the bottom plate projection.

In some aspects, the bottom plate projection includes a bolt having a threaded end that is received within a threaded opening defined in the bottom support plate.

In some aspects, the floor prop connecting plate is pivotable with respect to a longitudinal body of the bottom support prop and wherein, when connected, the floor prop connecting plate lies flat on the outer surface of the bottom support plate.

In some aspects, the top support prop and bottom support props are of a same configuration and are interchangeable.

In some aspects, in use, the bottom support prop extends downwardly in generally a same direction as the top support prop.

In some aspects, the top support plate and bottom support plate are interchangeable.

In some aspects, the techniques described herein relate to a method of constructing walls of an above ground level of a multi-level building, the method including: situating a top support plate on a top surface of a floor of the above ground level; situating a bottom support plate on a bottom surface of the floor of the above ground level; securing the top support plate to the bottom support plate, thereby sandwiching a portion of the floor of the above ground level therebetween; coupling a first end of a bottom support prop to the bottom support plate; coupling a second end of the bottom support prop to a load bearing structure associated with the multi-level building; coupling a first end of a top support prop to the top support plate; and coupling a second end of the top support prop to an inner surface of a pre-cast concrete slab wall substantially vertically positioned on the floor of the above ground level, wherein the top support prop extends diagonally from the top support plate to the pre-cast concrete slab wall, thereby supporting the pre-cast concrete slab wall during construction of the multi-level building.

The features and advantages of the present invention will become further apparent from the following detailed description of preferred embodiments, provided by way of example only, together with the accompanying drawings.

BRIEF DESCRIPTION OF THE DRAWINGS

Objects, features, and advantages of the disclosure will be readily apparent from the following description of certain embodiments taken in conjunction with the accompanying drawings in which:

FIG. 1 is an illustrative view of an upper level of a multi-level building showing part of a wall prop support system in accordance with some embodiments.

FIG. 2A shows an inner face of a support plate in accordance with some embodiments.

FIG. 2B shows an outer face of the support plate in accordance with some embodiments.

FIG. 2C is a perspective view showing top and bottom support plates in accordance with some embodiments.

FIG. 3 is a perspective view showing a section of floor of an upper level with bolt holes drilled therein in accordance with some embodiments.

FIG. 4 is a closeup view of the top support plate shown in FIG. 1 during positioning of the wall prop in accordance with some embodiments.

FIG. 5 is a closeup view of the top support plate shown in FIG. 1 with the wall prop secured thereto in accordance with some embodiments.

FIG. 6 is a closeup view showing attachment of the wall prop to the wall of FIG. 1 in accordance with some embodiments.

FIG. 7 is an illustrative view of a lower level of a multi-level building showing the remaining section of the wall prop support system of FIG. 1 in accordance with some embodiments.

FIG. 8 shows the support plate of FIG. 2A connected to a plurality of support props in accordance with some embodiments.

To facilitate understanding, identical reference numerals have been used, where possible, to designate identical elements that are common to the figures. It is contemplated that elements disclosed in one embodiment may be beneficially utilized in other embodiments without specific recitation. Moreover, the description of an element in the context of one drawing is applicable to other drawings illustrating that element.

DETAILED DESCRIPTION

Embodiments described herein relate to a wall support system for use in constructing walls of an above ground level of a multi-level building. Techniques described herein are suited for use with any construction method whereby the building comprises an above ground level having a floor supported by a floor truss system, such as described in the Applicant's afore-described Australian Patent No. 2021107586, which published on Jan. 6, 2022 and is hereby incorporated by reference in its entirety for all purposes.

An illustration of an upper level of a multi-level building having an upper wall panel 10 temporarily located on an above ground floor 12 is shown in FIG. 1. In this case, the above ground floor 12 comprises a timber floor surface 14 (e.g., comprising particle board sheets) supported by an underlying timber floor truss system 16 (see FIG. 7), formed using techniques well understood in the art. A depth of the individual floor trusses may vary from build to build but will typically range between 200 to 450 mm.

The upper wall panel 10 is typically lifted into position using a crane and may be temporarily supported by the crane until it has been connected to a wall support system as described herein. It will be understood that the upper wall panel 10 may form part of either an internal or external wall.

As shown in FIGS. 2A through 2C, the wall support system according to embodiments described herein comprises a top support plate 22 configured to locate on the timber floor surface 14 and a bottom support plate 24 configured to locate on a bottom surface of the floor 12 (i.e., underneath the top support plate 22 and typically bearing against a part of the floor truss system 16, such as a joist or beam). According to the illustrated embodiment, the top and bottom support plates 22, 24 are identical in shape and configuration and are formed of steel. An inner face 27 of the support plates is shown in FIG. 2A, while an outer face 29 is shown in FIG. 2B. In use, the inner face 27 of the top support plate 22 bears against the timber floor surface 14. The inner face 27 of the bottom support plate 24 bears against two or more bottom chords of adjacent floor trusses that span between opposing ground floor walls. Through holes 23 located inwardly of each corner are provided for receiving a securing means as described below. An additional pair of through holes 23a are provided to accommodate for differing truss spacing.

As is evident from FIGS. 1, 4 and 5, a projection 21 extends from the outer face 29 of each plate 22, 24, terminating in a flanged end. According to the illustrated embodiment, the projection 21 is removably coupled to each plate and takes the form of a bolt (preferably a high tensile steel bolt) having a threaded end that is received within a

threaded opening **25b** defined in a body of the respective plates **22, 24**. According to the illustrated embodiment, each plate includes a pair of threaded openings **25b** to accommodate multiple props (i.e., for supporting multiple walls), as will be described in more detail in subsequent paragraphs with reference to FIG. 8. To ensure sufficient threaded engagement, the threaded openings **25b** may extend beyond the inner face into (and through, if desired) bodies **31** that project from the inner face **27**, as shown in FIG. 2C. The threaded bodies **31** may, for example, be welded on to the plates **22, 24**.

In an alternative embodiment to that shown in the figures, the projection(s) **21** may be welded to, or otherwise integrally formed with, each plate **22, 24**.

As shown in FIG. 4, the wall support system further comprises a securing means **26** for joining the top and bottom support plates **22, 24**. In FIG. 4, the securing means **26** takes the form of one or more bolts (in this case four high tensile bolts **26a, 26b, 26c, 26d** for passing through corresponding holes **23** in each plate corner) that, in use, join the top and bottom support plates **22, 24** and can be tightened using nuts for sandwiching a portion of the floor **12** therebetween. It will be understood that the length of the bolts may vary depending on a depth of the floor truss system. FIG. 3 depicts a section of the timber floor surface **14** with holes **33** drilled therein for receiving the bolts **26a, 26b, 26c, 26d**, as well as holes **35** to accommodate the threaded bodies **31** that project from the inner face **27** of the top support plate **22**. It will be understood that other forms of securing means **26** may also be implemented. For example, a length of threaded rod with a washer and nut secured on either end could be used as the securing means **26** for joining the top and bottom support plates **22, 24**. Yet another form of securing means **26** could take the form of a G-clamp or other suitable clamping arrangement.

The wall support system further comprises a pair of support props **30, 32**. The props **30, 32** shown in the figures are interchangeable and thus identical in configuration. According to the illustrated embodiment, prop **30** is used for supporting the upper wall panel **10**, while prop **32** is used as a bracing prop and connects to a load bearing structure associated with the multi-level building. The load bearing structure will typically be the concrete floor slab **43** that forms the ground floor of the building.

More particularly, ends **34, 36** of each prop **30, 32** couple to a respective connecting plate **38** which is pivotable with respect to a longitudinal prop body. As shown, the props **30, 32** extend diagonally between the securing points and can operate in both compression and traction. The connecting plates **38** may be formed of steel or the like and are configured to pivot about a respective pivot pin which extends through each end **34, 36**. Each connecting plate **38** has an opening **39** for receiving either a securing means **26** or support plate projection **21**. The opening **39** may extend into a sidewall **41** thereof, thereby forming a channel for receiving a body of the plate projection **21** that facilitates sliding engagement therewith (see particularly FIG. 4).

A length of each prop **30, 32** is adjustable for reasons that will become evident in subsequent paragraphs. According to the illustrated embodiment, the props **30, 32** have an adjustable telescopic body consisting of an inner tube and outer tube with a cotter pin **45**, hitch pin or the like used for fast locking the tubes in place once a desired length has been achieved. At least one of the ends **34, 36** may also include a threaded section that can be rotated in and out of the telescopic body for fine tuning the length.

In use, and with particular reference to FIG. 7, an end **34** of the bottom support prop **32** is removably coupled to an outer face **29** of the bottom support plate **24** by sliding the corresponding plate **38** over the outer face **29** such that the projection **25** is guided into the channel and entrapped within the opening **39**. Where the projection **25** is a screw, it may thereafter be screwed down for securing the prop **32** to the bottom support plate **24**. The other end **36** is secured to the concrete floor slab **43**, e.g., by using a masonry screw, 10 chemical anchor, sleeve anchor, concrete screw bolt or other suitable concrete fastening member that extends through the opening **39** and into the slab **43**.

Similarly, and returning to FIG. 1, end **34** of the top support prop **30** is removably coupled to an outer face **22a** of the top support plate **22** using the same technique as described above for the bottom plate. The other end **36** is secured to an inner face of the upper wall panel **10** (see particularly FIG. 6). Again, this may be achieved by using a masonry screw, chemical anchor, sleeve anchor, concrete screw bolt or other suitable concrete fastening member that passes through the opening **39** and extends into the panel **10**. Alternatively, as shown in FIG. 6, the panel **10** may comprise a threaded ferrule precast in the inner wall and in this case a bolt **40'** may be used to secure the plate **38** to the panel **10**. Preferably, the bottom support prop extends downwardly in generally the same diagonal direction as the top support prop to suitably transfer a load of the upper wall panel downwardly towards the concrete floor slab.

It will be understood that the length of the props may be 30 adjusted to achieve a desired length for coupling and subsequently adjusted post coupling to achieve the necessary tension and vertical alignment of the upper wall panel **10** for installation. Once set, the wall prop system advantageously maintains vertical alignment of the pre-cast concrete and 35 prevents lateral movement wall during construction of the multi-level building.

As shown in FIG. 8, a top plate **22** may be connected to multiple props **30, 30'** for use in supporting multiple pre-cast concrete wall panels during construction of the multi-level building. It will be understood that the bottom plate **24** may 40 also couple to multiple props that extend diagonally in directions corresponding to the upper props **30, 30'** for suitably transferring the wall loads.

While a number of preferred embodiments have been 45 described, it will be appreciated by persons skilled in the art that numerous variations and/or modifications may be made to the invention without departing from the spirit or scope of the invention as broadly described. The present embodiments are, therefore, to be considered in all respects as 50 illustrative and not restrictive.

In the foregoing description and in the accompanying drawings, specific terminology has been set forth to provide a thorough understanding of the disclosed embodiments. In some instances, the terminology or drawings may imply 55 specific details that are not required to practice the invention.

To avoid obscuring the present disclosure unnecessarily, well-known components are shown in block diagram form and/or are not discussed in detail or, in some cases, at all.

Unless otherwise specifically defined herein, all terms are 60 to be given their broadest possible interpretation, including meanings implied from the specification and drawings and meanings understood by those skilled in the art and/or as defined in dictionaries, treatises, etc. As set forth explicitly herein, some terms may not comport with their ordinary or customary meanings.

As used in the specification and the appended claims, the singular forms "a," "an" and "the" do not exclude plural

referents unless otherwise specified. The word "or" is to be interpreted as inclusive unless otherwise specified. Thus, the phrase "A or B" is to be interpreted as meaning all of the following: "both A and B," "A but not B," and "B but not A." Any use of "and/or" herein does not mean that the word "or" alone connotes exclusivity.

As used in the specification and the appended claims, phrases of the form "at least one of A, B, and C," "at least one of A, B, or C," "one or more of A, B, or C," and "one or more of A, B, and C" are interchangeable, and each encompasses all of the following meanings: "A only," "B only," "C only," "A and B but not C," "A and C but not B," "B and C but not A," and "all of A, B, and C."

To the extent that the terms "include(s)," "having," "has," "with," and variants thereof are used in the detailed description or the claims, such terms are intended to be inclusive in a manner similar to the term "comprising," i.e., meaning "including but not limited to."

The terms "exemplary" and "embodiment" are used to express examples, not preferences or requirements.

The term "coupled" is used herein to express a direct connection/attachment as well as a connection/attachment through one or more intervening elements or structures.

The terms "over," "under," "between," and "on" are used herein refer to a relative position of one feature with respect to other features. For example, one feature disposed "over" or "under" another feature may be directly in contact with the other feature or may have intervening material. Moreover, one feature disposed "between" two features may be directly in contact with the two features or may have one or more intervening features or materials. In contrast, a first feature "on" a second feature is in contact with that second feature.

The term "substantially" is used to describe a structure, configuration, dimension, etc. that is largely or nearly as stated, but, due to manufacturing tolerances and the like, may in practice result in a situation in which the structure, configuration, dimension, etc. is not always or necessarily precisely as stated. For example, describing two lengths as "substantially equal" means that the two lengths are the same for all practical purposes, but they may not (and need not) be precisely equal at sufficiently small scales. As another example, a structure that is "substantially vertical" would be considered to be vertical for all practical purposes, even if it is not precisely at 90 degrees relative to horizontal.

The drawings are not necessarily to scale, and the dimensions, shapes, and sizes of the features may differ substantially from how they are depicted in the drawings.

Although specific embodiments have been disclosed, it will be evident that various modifications and changes may be made thereto without departing from the broader spirit and scope of the disclosure. For example, features or aspects of any of the embodiments may be applied, at least where practicable, in combination with any other of the embodiments or in place of counterpart features or aspects thereof. Accordingly, the specification and drawings are to be regarded in an illustrative rather than a restrictive sense.

The invention claimed is:

1. A wall support system for use in constructing walls of an above ground level of a multi-level building, the wall support system comprising:
  - a top support plate locatable on a top surface of a floor of the above ground level;
  - a bottom support plate locatable beneath the top support plate on a bottom surface of the floor of the above ground level;

a securing means for securing the top support plate to the bottom support plate, thereby sandwiching a portion of the floor of the above ground level therebetween; a bottom support prop having a first end configured to be coupled to the bottom support plate and a second end configured to be coupled to a load bearing structure associated with the multi-level building; and a top support prop having a first end configured to be coupled to the top support plate and a second end configured to be attached to an inner surface of a pre-cast concrete slab wall substantially vertically positioned on the floor of the above ground level, wherein the top support prop is configured to extend diagonally from the top support plate to the pre-cast concrete slab wall to support the pre-cast concrete slab wall during construction of the multi-level building.

2. The wall support system in accordance with claim 1, wherein a length of the top support prop is adjustable to set a vertical positioning of the pre-cast concrete slab wall.

3. The wall support system in accordance with claim 1, wherein the bottom support plate is configured to bear against a joist, beam, or other floor support structure.

4. The wall support system in accordance with claim 1, wherein the securing means comprises one or more bolts each having a threaded end that passes through a respective opening in the top support plate, extends through a hole in the floor of the above ground level and out a corresponding opening in the bottom support plate for receiving a nut.

5. The wall support system in accordance with claim 1, wherein the top support plate further comprises a top plate projection which extends upwardly from an outer surface terminating in a flanged end and wherein the first end of the top support prop comprises a connecting plate having an opening defined therein for receiving the top plate projection.

6. The wall support system in accordance with claim 5, wherein the top plate projection comprises a bolt having a threaded end that is received within a threaded opening defined in the top support plate and wherein the bolt is screwed into the threaded opening for securing the top support prop to the top support plate.

7. The wall support system in accordance with claim 5, wherein the connecting plate is pivotable with respect to a longitudinal body of the top support prop and wherein, in use, the connecting plate lies flat on the outer surface of the top support plate.

8. The wall support system in accordance with claim 7, wherein the second end of the top support prop comprises a connecting plate which is pivotable with respect to the longitudinal body of the top support prop and which comprises an opening defined therein for receiving the securing means for securing the top support prop to the inner surface of the pre-cast concrete slab wall.

9. The wall support system in accordance with claim 5, wherein the top support plate further comprises a second projection which extends upwardly from the outer surface of the top support plate and wherein the first end of a second top support prop comprises a connecting plate having an opening defined therein for receiving the second projection and such that in use a second end of the second top support prop connects to a second pre-cast concrete wall.

10. The wall support system in accordance with claim 1, wherein the bottom support plate further comprises a bottom plate projection which extends away from an outer surface terminating in a flanged end and wherein the first end of the

bottom support prop comprises a floor prop connecting plate having an opening defined therein for receiving a body of the bottom plate projection.

11. The wall support system in accordance with claim 10, wherein the bottom plate projection comprises a bolt having a threaded end that is received within a threaded opening defined in the bottom support plate. 5

12. The wall support system in accordance with claim 11, wherein the floor prop connecting plate is pivotable with respect to a longitudinal body of the bottom support prop and wherein, when connected, the floor prop connecting plate lies flat on the outer surface of the bottom support plate. 10

13. The wall support system in accordance with claim 1, wherein the top support prop and bottom support props are of a same configuration and are interchangeable. 15

14. The wall support system in accordance with claim 1, wherein, in use, the bottom support prop extends downwardly in generally a same direction as the top support prop. 20

15. The wall support system in accordance with claim 1, wherein the top support plate and bottom support plate are interchangeable. 25

16. A method of constructing walls of an above ground level of a multi-level building, the method comprising:

situating a top support plate on a top surface of a floor of the above ground level;

situating a bottom support plate on a bottom surface of the floor of the above ground level;

securing the top support plate to the bottom support plate, thereby sandwiching a portion of the floor of the above ground level therebetween;

coupling a first end of a bottom support prop to the bottom support plate;

coupling a second end of the bottom support prop to a load bearing structure associated with the multi-level building;

coupling a first end of a top support prop to the top support plate; and

coupling a second end of the top support prop to an inner surface of a pre-cast concrete slab wall substantially vertically positioned on the floor of the above ground level, wherein the top support prop extends diagonally from the top support plate to the pre-cast concrete slab wall, thereby supporting the pre-cast concrete slab wall during construction of the multi-level building.
